UNITED STATES PATENT OFFICE.

FRANK C. RONK, OF CANTON, OHIO.

REGULATOR-VALVE FOR GAS-BURNERS.

1,176,100.

Specification of Letters Patent. Patented Mar. 21, 1916.

Application filed August 29, 1914. Serial No. 859,199.

To all whom it may concern:

Be it known that I, FRANK C. RONK, a citizen of the United States, residing at Canton, in the county of Stark and State of Ohio, have invented a new and useful 5 Regulator-Valve for Gas-Burners, of which the following is a specification.

My invention relates to improvements in regulator valves for gas burners in which 10 the supply of gas is regulated by the pressure of steam and is more especially adapted to be used in connection with a gas burner for heating steam radiators and the like.

The object of this invention is to provide 15 a regulator valve by means of which the supply of gas is regulated by a pressure of steam.

Another object is to provide means for 20 automatically controlling the supply of fuel to the steam producing burner.

Another object is to provide adjustments by which the supply of fuel may be regulated with different pressures of steam.

With these objects in view the invention 25 consists in the novel construction and arrangement of parts, hereinafter described, illustrated in the accompanying drawings, and particularly pointed out in the appended claim, it being understood that various 30 changes in the form, proportions, size and minor details of construction may be made without departing from the spirit or sacrificing any of the advantages of the invention.

35 In the drawing: Figure 1 is a fragmentary sectional view of a portion of a steam radiator and gas burner showing my improved regulator valve in connection therewith. Fig. 2 is a sectional view of the regulator valve. Fig. 3 is an enlarged sectional view of the needle valve which automatically controls the pressure of gas. Fig. 4 is a similar view of the split needle valve which controls the flow of gas to the burner. Fig. 40 45 5 is a section on line 5-5, Fig. 3. Fig. 6 is a section on line 6-6, Fig. 4.

Similar numerals of reference indicate corresponding parts throughout the several views in the drawing.

50 In the accompanying drawing, 1 represents the lower portion of the end section of a steam radiator and 2 represents the adjoining sections which are connected in any suitable and well known manner as by the 55 rings 3 which allow communication between all of the sections as shown. A thimble 4

is screw threaded into the section 1 and a small section of pipe 5 which is connected to the regulator valve is slidably mounted within said thimble, extending into the interior of the radiator at a point above the water line, as shown in Fig. 1 of the drawing. The pipe 5 is connected by an elbow 6 and a short pipe 7 which is screw threaded into the neck 8 of the top 9 of the steam chamber casing. The body portion 10 of the steam chamber casing is provided with screw threads around its periphery by means of which an internally screw threaded cap 11 is connected thereto, said cap being provided with an inwardly disposed annular flange 12 which contacts with the shoulder 13 of the top 9, clamping said top upon the body portion 10 of the casing. A flexible diaphragm 14 preferably composed of thin 75 sheet metal is provided with the off set flange 15 which is adapted to rest between the shoulder 16 of the steam chamber casing 10 and the cap 9; a gasket 17 being preferably interposed between said flange 15 and 80 the cap for the purpose of making a steam tight joint.

A screw threaded nipple 18 is provided upon the lower extremity of the casing 10, to which is attached the portion 19 of the 25 valve casing. To the portion 19 of the valve casing is attached a supply pipe 20 by means of a union or elbow 21 as shown, said elbow being connected to the casing by means of the screw threads 22. The supply 90 pipe is connected to any suitable source of supply such as street pipes properly connected to a gasometer or other source of supply, reference being had to the kind of gas employed. A cut-off valve 23 is located 95 in the casing 19 and is adapted to be operated by means of a handle 24, said valve being for the purpose of shutting off the supply of gas to the valve when desired.

A spring chamber 25 is provided in the 100 casing and a concentric cylindrical bore 26 communicates therewith. A needle valve 27 is located through the cylindrical bore 26 and is provided upon its upper extremity with a thimble 28 which bears against the 105 diaphragm 14. The thimble has an annular flange 29 around its upper edge and a spring 30 is interposed between said flange and the lower wall 31 of the spring chamber. The lower extremity of the needle 27 is 110 tapered at 32 and provided with a reduced point 33, the tapered end 32 being located

within the conical valve seat 34 and the point 33 in the reduced aperture 35, which communicates with the chamber 36 which will hereinafter be described. A chamber 5 37 communicates with the gas supply line 20 through the channel 38 when the shut-off valve 23 is open.

The valve 27 is provided with transverse grooves 39 preferably located at right angles as shown in Fig. 5 and extending longitudinally through the needle to a point within the nipple 18. An inlet port 40 is located in the needle 27 and forms a communication between the chamber 37 and the 15 central channel 41 of the needle.

A regulating needle valve 42 provided with a screw threaded portion 43 is located through the chamber 36, the screw threaded portion 43 being engaged by the internal 20 screw threads 44 and a stuffing box 45 being located around said screw threaded portion for the purpose of forming an air tight joint. The needle 42 is constructed similar to the needle 27 having a pair of transverse 25 slots 46 extending longitudinally therethrough to a point within the chamber 36, an inlet 47 forming communication between the chamber 36 and the central channel 48 of the needle. The needle 42 is tapered at 30 49 and provided with the reduced point 50, said tapered portion being located within the valve seat 51, the reduced point 50 being situated within the aperture 52, the opposite 35 end of the needle valve being provided with a squared head 53 by means of which the needle may be rotated for the purpose of regulating the flow of gas therethrough. This needle valve 42 I do not claim as my invention in this application.

40 An ordinary mixer 54 is connected upon the neck 55 in any suitable and well known manner and provided with the usual apertures 56 to allow the admission of air. A tube 57 is connected with the mixer and 45 passes through the aperture 58 in the lower chamber 59 of an ordinary "Bunsen" burner 60. The tube 57 is slidably mounted within the aperture 58 and is held in position by means of a set screw 61, and the inner open 50 extremity of the tube is covered with a wire gauze 62 for the purpose of preventing the flame from passing back into the valve in the event that the gas pressure becomes low. The burner 60 is supported within a sheet 55 metal housing 63 which may be attached to the lower portion of the radiator sections in any suitable and well known manner and is adapted to retain the heat of the burner 60.

The operation of the device is as follows: 60 When the steam pressure becomes lower than desired, thereby reducing the radiation, the spring 30 will cause the needle 27 to move upwardly causing the tapered extremity 32 of the needle to be moved out of 65 the conical seat 34 thus allowing the split

ends of the needle to spring away from each other, enlarging the central aperture 41 through the needle and admitting a greater supply of gas to the burner, increasing the steam pressure. When the steam pressure 70 has reached the desired point, the pressure upon the diaphragm 14 will move the diaphragm and the needle 27 downwardly forcing the tapered end 32 of the needle into the conical seat 34, thereby reducing the central 75 channel 41 in the needle and thus reducing the supply of gas to the burner. It will be noted that by this construction of split needle valve, the supply of gas to the burner will never be entirely cut-off automatically, 80 the channel 41 always allowing enough gas to pass into the burner to keep the burner lighted. In the ordinary form of needle valve sufficient pressure upon the needle would entirely close the valve and cut off 85 the entire supply of gas to the burner, thus extinguishing the light in the burner. As the steam pressure is reduced and the needle valve opened a supply of gas would again be admitted to the burner and the gas would 90 continue to escape, thus often occasioning accident.

It is well understood that in heating systems, the degree of heat desired varies from time to time, owing to different degrees of 95 temperature and during excessive cold weather more heat is required than is necessary during periods of moderate temperature. In order to provide for the proper regulation of the heat with reference to 100 weather conditions the adjustable thimble 28 is provided, which thimble is located upon the needle 27 and is provided with the flange 39, which flange forms an abutment for one end of the spring 30, the opposite 105 end of said spring abutting against the inner end of the valve casing 31.

It will be understood that by adjusting the thimble in opposite directions, the tension of the spring will be increased or decreased, reference being had to the adjustment of the thimble, by which adjustment greater or less steam force is required so that the degree of heat may be automatically regulated to produce the desired 115 amount of heat, reference being had to weather conditions as to heat and cold.

The tube 57 is adjustably mounted within the aperture 58 of the burner in order to increase or decrease the pressure of gas to 120 the burner by reason of the siphoning effect. When the tube 57 is moved farther into the burner the gas will be brought closer to the point of combustion, thereby increasing the pressure. As the tube is withdrawn the gas 125 is injected into the burner farther from the point of combustion, thus decreasing the pressure. This tube 57 I do not claim as my invention.

Although the drawings and above specifi- 130

cation disclose the best mode in which I have contemplated embodying my invention I desire to be not limited to the details of such disclosure, for, in the further practical 5 application of my invention, many changes in form and construction may be made, as circumstances require or experience suggests, without departing from the spirit of the invention, within the scope of the appended claim.

10 I claim:

In combination with a valve casing provided with a conical valve seat and an internal shoulder, a flexible diaphragm located 15 within said casing, a needle slidably mounted within said casing and provided with a tapered extremity adapted to fit said conical valve seat, said tapered portion of the needle being split longitudinally in planes

at right angles to each other and provided 20 with a central longitudinal channel connected therewith, a thimble provided with longitudinal slots and adapted to frictionally engage the other extremity of said needle in any desired adjustment, the upper extremity of said thimble contacting with said flexible diaphragm, an annular flange provided upon said thimble and a coil spring located between said flange and the internal shoulder in said casing.

25 In testimony that I claim the above, I have hereunto subscribed my name in the presence of two witnesses.

30 FRANK C. RONK.
